UNITED STATES PATENT OFFICE.

AMOS RANK, OF SALEM, OHIO.

DESIGN FOR GRAVE-GUARDS.

Specification forming part of Design No. 7,780, dated September 29, 1874; application filed August 28, 1874.
[Term of Patent 14 years.]

CASE C.

To all whom it may concern:

Be it known that I, AMOS RANK, of Salem, in the county of Columbiana and State of Ohio, have invented a Design for Grave-Guards, of which the following is a specification:

The nature of my invention is fully represented in the accompanying drawing, to which reference is here made.

The guard is nearly or quite flat, as concerns its upper and under surfaces. Its ends are squared across from *a* to *a*—that is to say, formed in straight lines transverse to the length of the guard—the one end, *A*, being of greater width than the other or opposite end, *B*. The sides are curved outward with a moderate curvature, this latter being greatest adjacent to the broader end *A*, and less or more nearly approaching a straight line as it nears and finally joins the end *B*. The corners of the guard are thereby formed with nearly acute

angles. The upper surface of the guard is narrower and shorter than the under surface thereof, so that the circumferential surface of the same is made flaring, or sloping outward and downward, as fully shown in the drawing. The central portion of the guard is hollowed out to form a space, *A*, which, circumferentially, may, more or less, correspond in shape to the external circumferential outline of the guard.

What I claim as my invention is—

The design for a grave-guard, in which the outer circumferential surface is formed with ends squared across, and sides formed on a continuous outward curve, in the manner substantially as herein set forth.

AMOS RANK.
